UNITED STATES PATENT OFFICE

95,257

DESIGN FOR A MEAT AND FOOD TENDERING MACHINE

John C. Hintz, River Forest, Ill., assignor to Tenderet Corporation, Chicago, Ill., a corporation of Illinois

Application January 24, 1935, Serial No. 55,040

Term of patent 14 years

To all whom it may concern:

Be it known that I, John C. Hintz, a citizen of the United States of America, and a resident of River Forest, Cook County, Illinois, have invented a new, original, and ornamental Design for a Meat and Food Tendering Machine, of which the following is a specification, reference being had to the accompanying drawing, forming a part hereof.

The figure of the drawing is a perspective view of the meat and food tendering machine showing my new design.

I claim:

The ornamental design for a meat and food tendering machine substantially as shown.

JOHN C. HINTZ.
